CLAIM

The ornamental design for a valve assembly and swirl chamber as shown and described.

DESCRIPTION

FIG. 1 is a perspective view of a first end of a valve assembly and swirl chamber showing our new design;

FIG. 2 is a perspective view of a second end, opposite the first end thereof;

FIG. 3 is a first side view thereof;

FIG. 4 is a second side view, opposite the first side thereof;

FIG. 5 is a top view thereof; and,

FIG. 6 is a bottom view, opposite the top thereof.

The broken lines shown in the drawings depict portions of the valve assembly and swirl chamber that form no part of the claim.
